UNITED STATES PATENT OFFICE

151,071

DESIGN FOR A CHILD'S BOOT OR SIMILAR ARTICLE

Henri E. Rosen, Brookline, Mass.

Application March 25, 1947, Serial No. 137,857

Term of patent 7 years

(Cl. D7—7)

To all whom it may concern:

Be it known that I, Henri E. Rosen, a citizen of the United States of America, residing at Brookline, in the county of Norfolk and Commonwealth of Massachusetts, have invented a new, original, and ornamental Design for a Child's Boot or Similar Article, of which the following is a specification, reference being had to the accompanying drawings forming a part thereof, and wherein

Fig. 1 is a left-side elevational view of a child's boot, showing my new design;

Fig. 2 is an elevation of the right-hand side of the boot of Fig. 1;

Fig. 3 is a top plan view of the boot of Fig. 1; and

Fig. 4 is a rear elevation of the boot of Fig. 1.

The dominant feature of the design is the spur whose supporting bracket appears as a part of the

shoe itself and whose rowel teeth are dull at their tips.

I claim:

The ornamental design for a child's boot or similar article, substantially as shown and described.

HENRI E. ROSEN.
